United States Patent Office

Des. 178,691
Patented Sept. 4, 1956

178,691

DIVING TOWER

James A. Patterson, Columbus, Ohio

Application March 8, 1955, Serial No. 34,953

Term of patent 14 years

(Cl. D14—3)

Fig. 1.

Fig. 2.

Fig. 3.

Fig. 4.

Fig. 1 is a top plan view of a diving tower embodying my new design.

Fig. 2 is a side elevational view thereof.

Fig. 3 is a front elevational view thereof, and
Fig. 4 is a rear elevational view thereof.

I claim:

The ornamental design for a diving tower, as shown.
